J. J. MILLER

BLEEDER VALVE

Filed March 15, 1927

Fig. 1.

INVENTOR
JEROME J. MILLER

By *Murphy*
ATTORNEY

UNITED STATES PATENT OFFICE.

JEROME J. MILLER, OF CHADRON, NEBRASKA.

BLEEDER VALVE.

Application filed March 15, 1927. Serial No. 175,618.

This invention relates to a bleeder valve and means for lubrication of an air brake cylinder and has for its object the provision of a quick and reliable means for emptying the air brake air cylinders of railroad cars of air and water and to lubricate the cylinder.

Other uses will be apparent to those skilled in the art and lie within the scope of my invention.

At present railroad cars are bled in this manner. A man stands at the side of the car and holds open the bleeder valve by pulling on a rod attached to the valve stem or rocker arm of such valve until the air is all out of the cylinder which releases the brakes. The object is to release the brakes preparatory to handling cars without air brakes. By the use of my invention this operation is done automatically.

In the accompanying drawings:—

Figure 1 illustrates a side elevation in section of an air brake cylinder with my improved valve mounted thereon and showing the hollow piston rod of the air brake cylinder with the lubricating means in position.

Figure 2 is an enlarged view of the bleeder valve from the same position as shown in Fig. 1 and more clearly illustrates the trip means employed to keep the valve open while functioning.

Figure 3 is a front end elevation of the invention.

Figure 4 is a perspective view of the trigger for opening and closing the valve.

Figure 5 shows a perspective view of the trip means taken from the left and looking down on same.

Figure 6 shows a view of the bleeder valve in running position, that is, with the trip means idling while in running position.

Referring now to Figure 1, numeral 1 indicates an air brake cylinder of usual construction, having a portion 1* containing a piston 2 having a hollow piston rod 3. A bleeder pipe 4 extends back over the cylinder to its rear end and on the end of this bleeder pipe, the bleeder valve 5 is located. On the piston rod 3 a trip 6 is mounted and inside the piston rod a plug 7 of grease is placed. Slidable in the piston rod behind the plug 7 is a follower 8 provided with an eye bolt 9* at the rear end to facilitate removal of the plug. The eye bolt is disposed in a recess 2 in the rear end of the follower so that its

end does not project. A plunger 9 is slidable within the hollow piston 3 and is arranged so that during the action of the brake, a pressure is transmitted to the plug of grease and the follower 8 to force lubricant through 60 a channel in the piston to the walls of the cylinder.

A valve body or shell 10 is provided which is bifurcated at its upper end to provide a pair of parallel transversely extending plates 65 10', and arranged upon opposite sides of the valve body or shell is a pair of weighted arms 13 having their upper ends pivotally supported between the plates 10' and provided with inwardly directed lateral extensions or lugs 19 arranged in over-lapped relation and normally extending horizontally between the plates.

The body or shell of the valve is screwed onto the end of the bleeder pipe by means 75 of the union 11, through the medium of a short length of pipe extending upward into the valve and screwed thereto as shown at 15. In the valve body 10, the central portion 16 into which the screw connection 15 fits is 80 provided with a central hole into which a bleed valve 17 fits, bearing a nut or pin at its upper end. The short arms or lugs 19—19 of the rockers 13—13 contact with the top of the valve 17 which is ordinarily 85 held seated by the air pressure. In this figure the tripping means is shown at 18 being a flat square member, as in Fig. 5, provided with spring clips 14, a pair of staffs, a short section of which at the bottom is 90 turned at right angles as shown at 4.

Figure 4 shows the trigger, it consisting essentially of a bridge 20 secured upon the upper edges of the plates 10' carrying a pair of longitudinally curved latch arms 21 95 each of which carries a laterally extending lug 22 and a grasping element 27 adjacent its rear end.

Describing now the lubricating device, 7 is 100 a plug of grease in the hollow piston rod 3, the end nearest the piston being provided with circumferential holes; 24 is a passage-way leading to a porous gasket 25 in contact with the cylinder wall. The piston 9 is pushed in to spread the grease through 105 the channel 24 by the action of the brake transmitted through a solid rod operating inside the hollow piston rod.

The operation of the bleeder is as follows:

When the piston 2 is in the position shown 110

in Fig. 6, the flat panel 18 of the trip engages the ends 12^a of the trigger 12 and pushes them upward, thus sliding the cam portion 22 from under the arms 13, and allowing them to drop somewhat until they strike the clips 14 now also under the arms 13 and thereby retain the arms against accidental swinging movement incident to the vibration of the train, thus obviating premature actuation of the valve 17. The clips 10 protect the arms from locking and tampering.

The arms 13 being now depressed, there is no pressure being exerted on the top of 15 valve stem 17, thus allowing this valve stem to remain closed by the spring pressure. When the trip is in as close engagement with the bleeder valve as is possible, the trigger ears 21 are swung a maximum distance 20 toward the cylinder. When the trip is retracted, the ears fall again and the lugs on their sides slide under the rocker arms 13 and lift them up, depressing the valve 17 and letting out the air and any water that may 25 be present.

I claim:—

1. In combination an air brake cylinder provided with a normally closed bleed valve and a piston reciprocable in the cylinder, a 30 pivoted valve depressing element, and a manually set latch element pivotally supported for movement in a direction at right angles to the plane of movement of the valve depressing element and adapted to actuate 35 and retain the valve depressing element in position to depress the valve to open position, and an abutment carried by the piston for actuating the latch element to a position to render the valve actuating element inactive and permit the valve to close.

2. In combination an air brake cylinder having a normally closed bleed valve, and a piston reciprocable in the cylinder, a valve actuating element pivotally supported adjacent the valve, a manually set latch element 45 movable at right angles to the valve actuating element and having a bevelled surface to engage and actuate the actuating element to a position to retain the bleed valve open, 50 and an abutment carried by the piston rod arranged to actuate the latch to disengage its bevelled surface from the valve actuating element permitting closing of the valve upon movement of the piston in an inward 55 direction.

3. In combination an air brake cylinder having a normally closed bleed valve and a

reciprocable piston in the cylinder, a valve actuating element pivoted adjacent the valve, a latch element pivotally supported for 60 movement at right angles to the valve actuating element and arranged to lift the latter against the valve to retain it in open position upon being set in a forward position, and a fixed abutment carried by the piston rod 65 and arranged to swing the latch element in a rearward direction disengaging it from the valve actuating element.

4. In a valve actuating device, a normally closed reciprocable valve, a pair of valve 70 actuating elements pivoted adjacent the valve, a swinging latch supported adjacent the valve actuating elements and arranged to actuate and latch the valve actuating elements in position to retain the valve in open 75 position, and means for disengaging the latch from the valve actuating elements to permit the valve to return to closed position.

5. In combination an air brake mechanism including a pressure cylinder, a normally 80 closed bleed valve and a reciprocable piston, a plurality of weighted valve actuating elements supported adjacent the valve, a pair of longitudinally curved latch arms pivotally 85 supported for movement at right angles to the valve actuating elements and adapted to lift and latch the arms in a position to retain the valve open, and an upstanding abutment carried by the piston rod for engagement with the latch arms to disengage the latter 90 from the valve actuating elements upon movement of the piston rod in an inward direction.

6. In combination an air brake mechanism including a pressure cylinder, a normally 95 closed bleed valve and a reciprocable piston, a plurality of weighted valve actuating elements supported adjacent the valve, a pair of longitudinally curved latch arms pivotally 100 supported for movement at right angles to the valve actuating elements and adapted to lift and latch the arms in a position to retain the valve open, an upstanding abutment carried by the piston rod to disengage the latch arms from the valve actuating elements upon movement of the piston in one 105 direction, and a pair of forwardly projecting arms carried by the abutment and disposed behind the valve actuating elements when the piston is at the end of its movement in one direction to prevent the latter 110 from prematurely actuating the valve.

JEROME J. MILLER.
